UNITED STATES PATENT OFFICE.

GREENLEAF WHITTIER PICKARD, OF AMESBURY, MASSACHUSETTS.

SOLID RECTIFIER FOR FEEBLE ELECTRIC CURRENTS.

1,137,714.

Specification of Letters Patent.

Patented Apr. 27, 1915.

Application filed March 9, 1907. Serial No. 361,444.

To all whom it may concern:

Be it known that I, GREENLEAF WHITTIER PICKARD, a citizen of the United States of America, and a resident of the town of Amesbury, State of Massachusetts, have invented certain new and useful Improvements in Solid Rectifiers for Feeble Electric Currents, the principles of which are set forth in the following specification and accompanying drawings, which disclose the form of the invention which I now consider to be the best of the various forms in which said principles may be embodied.

This invention relates to oscillation-detecting means for receiving intelligence communicated by electric waves, as by wireless telegraphy or telephony.

The object of the invention is to provide an improved form of holder for use as detectors of the class disclosed in my Patent No. 836,531 of November 20, 1906.

The invention consists of mechanical holders, substantially as herein described.

Of the drawings, Figure 1 is a vertical section of a complete embodiment of the invention, and Fig. 2 is a plan of the same.

The operating conducting members are shown at A and B, and may be of brass and silicon respectively, or of equivalents. The binding posts for the circuit terminals are at E and E', Figs. 2 and 1, and the circuits may be any suitable ones, such as disclosed in my patent above specified. The permanent leads, A' from member A, and B' from member B, (Fig. 2) lie in the insulating base I, in holes drilled horizontally from the recesses for the heads of screws H and D to the recesses for the heads of the binding posts.

The member A is mounted in the bracket Z, being confined by a sliding fit in a sleeve support, or plunger L, which in turn is confined and has a sliding fit in the guide G which constitutes the end of bracket Z, this bracket being secured to the insulating base I by the screw D and pin N'. A metallic helical spring S is held between the cap or finger piece C (which is integral with or soldered to sleeve L), and the top of conducting rod A. Conductor A enters sleeve L from below and is pressed downward into substantially perfect contact with member B at any point such as T J. The conductor A is unrestrainedly adjustable up and down in plunger L within the elastic limits of spring S. The operator, his finger

on cap C, by alternate successive depressing and release of pressure, obtains the optimum degree of perfect contact as indicated by the response in the indicating instrument connected to leads E, E'. As soon as this definite state of spring pressure is obtained, the operator instantly fixes the spring in this state by a slight quick turn of clamping screw W, which clamps plunger L in guide G and prevents further variation of spring pressure. After this adjustment is made and fixed, the device will remain properly operative for indefinite periods under substantially constant operating conditions. The lower end of support L, by its ability to abut against conductor B, serves to prevent adjustment beyond a predetermined degree of pressure which might injure the surfaces of the conductors, particularly the polished surface of conductor B.

The conductor B, which may be the pure natural element silicon, or an equivalent sensitive conductor of high resistivity, is embedded in fusible metal M in the metal cup P, which cup rests on the metallic conducting base K held to insulating base I by screw H and pin N. The pressure of spring S keeps in good contact the bottom of cup P and the top of conducting base K. The cup P is unrestrainedly movable manually in the plane of the top of base K. After the operator has obtained the optimum spring pressure, as described above, he slides the cup P about on top of base K, to find the optimum place of contact of conductor A on the surface of conductor B, which surface is level to maintain uniform pressure of spring S, and may be polished. In Fig. 2 the cup P is shown offset from a central position, this being one of the many positions to which the operator may freely move it with his fingers.

Of course, various mechanical equivalents of the holder hereof may be made, which will substantially possess the essential features of the invention. While the perfect contact detector may be usefully employed without all the mechanical features of this invention, it is believed that the holder herein disclosed is the most advantageous one in which to employ most of the substances which may be used as members of the perfect contact detector.

I claim:

1. A holder for an electrical oscillation

- detector of the contact type, comprising in combination, means for supporting one contacting conductor in a fixed position with respect to movement toward the other; a sleeve plunger in which the other contacting conductor is mounted and confined so as to be adjustable only to and from the fixed conductor; a guide in which the sleeve plunger is mounted and confined so as to be adjustable only to and from the fixed conductor; and a spring held inside the sleeve plunger and pressing the adjustable conductor against the fixed conductor, said sleeve plunger and spring being proportioned to prevent an adjustment of pressure exceeding a predetermined maximum, and said guide being fixedly supported to prevent unrestrained bodily movement relative to its support.
- 20 2. A holder for an electrical oscillation detector of the contact type, comprising in combination, a spring pressing one contacting conductor against the other; means for fixing the spring at a definite state of pressure; said spring being unrestrainedly adjustable, when not held by said fixing means, within wide limits of pressure; and means permitting the contact of one conductor with various different parts of the opposing surface of the other conductor.
- 30 3. A holder for an electrical oscillation detector of the contact type, comprising in combination, an insulating base; means for mounting one of the two detector-conductors on said base and providing a low resistance contact with the circuit terminal; a bracket mounted on said base and carrying a guide; a supporting plunger, mounted in the guide, for the second detector-conductor, and adjustable only to and from the first conductor; the second conductor being movable in said supporting plunger only to and from the first conductor; means for pressing the second conductor against the first conductor; and means for permitting the contact of one conductor with various different parts of the opposing surface of the other conductor.
- 40 4. A holder for an electrical oscillation detector of the contact type, comprising in combination, a spring pressing one of the contacting conductors against the other; means for fixing the spring at a definite state of pressure; a supporting plunger for the spring, said plunger and spring being unrestrainedly adjustable, when not held by said fixing means, within wide limits of spring pressure; and means for permitting the contact of one conductor with various different parts of the opposing surface of the other conductor.
- 50 5. A holder for an electrical oscillation detector of the contact type, comprising in combination, a spring pressing one conductor against the other; means for fixing the
- 60 6. A holder for an electrical oscillation detector of the contact type, comprising in combination, a helical spring pressing one contacting conductor against the other; means for fixing the spring at a definite state of pressure; a sleeve plunger in which the helical spring is mounted; a guide in which the plunger is unrestrainedly movable within wide limits when not held by said fixing means; and means for permitting the contact of one conductor with various different parts of the opposing surface of the other conductor.
- 70 7. A holder for an electrical oscillation detector of the contact type, comprising in combination, a helical spring pressing one contacting conductor against the other; means for fixing the spring at a definite state of pressure; a sleeve plunger in which the helical spring is mounted and which receives a portion of one of the detector-conductors so that the spring operates between the plunger and such conductor; a guide in which the plunger is unrestrainedly movable within wide limits when not held by said fixing means; and means for permitting the contact of one conductor with various different parts of the opposing surface of the other conductor.
- 80 8. A holder for an electrical oscillation detector of the contact type, comprising in combination, a helical spring pressing one contacting conductor against the other; means for fixing the spring at a definite state of pressure; a sleeve plunger in which the helical spring is mounted and which receives a portion of one of the detector-conductors; a guide in which the plunger is unrestrainedly movable toward the other detector-conductor when not held by said fixing means; and means for permitting the contact of one conductor with various different parts of the opposing surface of the other conductor.
- 90 9. A holder for an electrical oscillation detector of the contact type, comprising in combination, a plunger; a spring operated by the plunger to press one contacting conductor against the other; a guide in which the plunger is freely adjustable toward the conductors; a clamp to fix the plunger at any desired position in the guide; and means for permitting the contact of one conductor with various different parts of the opposing surface of the other conductor.
- 100 10. A holder for an electrical oscillation detector of the contact type, comprising in combination, a plunger a spring operated by

the plunger to press one contacting conductor against the other; a guide in which the plunger is freely adjustable within wide limits; means, operable at will, to fix the plunger in any desired position in the guide; and means for permitting the contact of one conductor with various different parts of the opposing surface of the other conductor.

11. A holder for an electrical oscillation detector of the contact type, comprising in combination, two coöperating solid contacting conductors, one of which is unrestrainedly movable in a definite plane; a spring pressing against the other conductor; a plunger between which and the second conductor the spring is located; a guide in which the plunger is unrestrainedly movable toward the first conductor; means, operable at will, to fix the plunger in the guide; and means for permitting the contact of one conductor with various different parts of the opposing surface of the other conductor.

12. A holder for an electrical oscillation detector of the contact type, comprising in combination, a spring pressing one conductor against the other; means for instantly fixing the spring at a definite state of pressure; said spring being unrestrainedly adjustable, when not held by said fixing means, within wide limits of spring pressure; means for preventing a spring-pressure in excess of a predetermined maximum; and means for permitting the contact of one conductor with various different parts of the opposing surface of the other conductor.

13. A holder for an electrical oscillation detector of the contact type, comprising in combination, the two contacting conductors, means for fixing one of the detector-conductors from all movement except to and from the second detector-conductor; a conducting base on the surface of which the second conductor is unrestrainedly movable, said second conductor having a level surface engaging the first conductor; a spring pressing the first conductor against the second conductor, and thereby pressing the second conductor against its conducting base to hold it in a fixed operative position; and means for permitting the contact of one conductor with various different parts of the opposing surface of the other conductor.

14. A holder for an electrical oscillation detector of the contact type, comprising in combination, a spring which operatively holds the two contacting conductors in contact with each other; a freely-movable non-threaded adjusting plunger for the spring; means for fixing said plunger against adjusting movement; and means for permitting the contact of one conductor with various different parts of the opposing surface of the other conductor.

15. A holder for an electrical oscillation-

detector of the contact type, comprising in combination, an extension from one of the contacting conductors, a support containing the same and normally affording free relative movement for said parts in a direction to and from the operating contact, a spring acting to press said extension through said support toward the coöperating contacting conductor to effect an operative normally fixed and small-area contact, means whereby said support is adjustable to vary the effect of said spring; and means normally permitting manual relative movement of the contacting conductors to permit selection at will of various contact points on the surface of one of the contacting conductors.

16. A holder for an electrical oscillation detector of the contact type, which comprises, in combination with the two effective contacting conductors, a helical spring arranged to cause one conductor to press against the other, means for freely and unrestrainedly adjusting said spring within wide limits of contact-pressure; means for normally fixing said spring against pressure-varying movement; and means for supporting said other conductor and maintaining its connection in circuit, while permitting said conductor to be freely and unrestrainedly moved about at will into various different points of contact with the spring-controlled conductor.

17. In an oscillation detector, the combination with two contacting conductors, one having a substantially flat contact face and the other a substantially point contact arranged to extend toward the contact face of the first; of a helical spring arranged to press the said two conductors together; and a holder for the conductor which has a substantially flat contact face, constructed to expose the contact face toward said point contact, and arranged to be movable laterally relative to said point contact to present thereto all parts of the contact face of the combined contacting conductor.

18. A holder for an electrical oscillation detector of the contact type, comprising in combination, a helical spring acting to press one contacting conductor against the other; a sleeve constructed independently of the contact conductors and containing said helical spring, and in which the spring is always freely movable, said sleeve being provided with a fixed abutment for that end of the spring which is the more remote from the contacting conductors; means for holding said sleeve in different positions variously distant from the other contacting conductor to adjust the effective contact pressure of the spring, all whereby the spring can be compressed and its contacting conductor be withdrawn from the opposing surface of the other contacting conductor, without altering the effective contact pres-

- sure of the spring; and means permitting the contact of one contacting conductor with various different parts of the opposing surface of the other contacting conductor.
- 5 19. A holder for an electrical oscillation detector of the contact type, comprising in combination, a helical spring acting to press one contacting conductor against the other; a sleeve constructed independently of the 10 contact conductors and containing said helical spring, and in which the spring is always freely movable, said sleeve being provided with a fixed abutment for that end of the spring which is the more remote from 15 the contacting conductor; and means for holding said sleeve in different positions variously distant from the other contacting conductor to adjust the effective contact pressure of the spring, all whereby the 20 spring can be compressed and its contacting conductor be withdrawn from the opposing surface of the other contacting conductor, without altering the effective contact pressure of the spring.
- 25 20. In an oscillation detector the combination with two contacting conductors, one having a substantially flat contact face and the other a substantially point contact, arranged to extend toward the contact face of 30 the first; a helical spring arranged to press the two contacts together; a device, additional to the contacting conductors themselves, for holding and inclosing said spring; and means constructed and arranged to permit the movement of one contact transversely of the other, and thereby permit the point contact to engage with all parts of the face contact.
21. In an oscillation-detector of the contact type, the combination with an operating conductor normally in fixed and small-area contact with a second conductor, of a 40 sleeve, a helical spring inclosed in the sleeve and determining the operating pressure of the contact, a sleeve-support in which the sleeve is mounted to move for spring-adjustment, means for fixing the sleeve in its adjusted position, and means normally permitting manual relative movement of the 45 contacting conductors to permit selection at will of various contact points on the surface of the operating conductor.
22. In an oscillation-detector of the contact type, the combination with a sleeve, of 50 a helical spring inclosed in the sleeve and determining the pressure of the operating contact, a sleeve-support in which the sleeve is mounted to move for spring-adjustment, a rod mounted in the sleeve to permit relative sliding movement of the sleeve and rod, 55 said rod being pressed by the spring to effect fixed and small-area operating contact, and means normally permitting man-
- 60 ual relative movement of the contacting conductors, to permit selection at will of various operating contact points.
23. In an oscillation-detector of the contact type, the combination with an operating conductor normally in fixed and small-area contact with a second conductor, of a 65 sleeve, a support for the sleeve intermediate the ends thereof and in which the sleeve is movably adjustable, a conducting member slidably mounted in the sleeve and extending through an end thereof toward the operative contact, a helical spring inclosed in the sleeve and pressing said conducting member through the end thereof toward said operative contact, and means normally permitting manual relative movements of 70 the contacting conductors to permit selection at will of various contact points on the surface of one of the contacting conductors.
24. In wireless telegraphy, a wave responsive device comprising a mass of detecting 75 material, and a relatively eccentrically mounted coöperating member comprising an electrically conducting element, and means to hold the two members so that at least one of them shall have a relative rotative or lateral movement, and so that at least one of them shall have a relative longitudinal movement in a line parallel with but eccentric to the wave detecting material or the electrical conductor axis, in combination 80 with means to hold at least one of said members under tension and to adjust them to make a good contact between the wave detecting material and the electrically conducting element in a line not coincident with both of the axes of the same.
25. In wireless telegraphy, a wave responsive device comprising a mass of detecting 85 material, and a relatively eccentrically mounted coöperating member comprising an electrically conducting element, and means to hold the two members so that at least one of them shall have a relative rotative or lateral movement, and so that at least one of them shall have a relative longitudinal 90 movement in a line parallel with but eccentric to the wave detecting material or the electrical conductor axis, in combination with means to hold at least one of the said members under tension and to adjust them to 95 make a good contact between the wave detecting material and the electrically conducting element in a line not coincident with both of the axes of the same, one at least of the said members being of greater diameter 100 at the base of the same than at the operative junction of the members.
